Primary Examiner—Ralf Seifert*Attorney, Agent, or Firm*—Howard C. Miskin[57] **CLAIM**

The ornamental design for a two stone jewelry setting, as shown and described.

DESCRIPTION

FIG. 1 is a top plan view of a jewel setting, showing my design;

FIG. 2 is a front elevational view of this design, the opposite side view being a mirror image;

FIG. 3 is a side elevational view, the opposite side view being a mirror image;

FIG. 4 is a bottom plan view;

FIG. 5 is a top right side perspective view;

FIG. 6 is a top right perspective view shown in a position of use, the broken line showing of a finger ring is for illustrative purposes only and forms no part of the claimed design;

FIG. 7 is a top plan view shown in position of use, the broken line showing of a tether and attachment loop is for illustrative purposes only and forms no part of the claimed design;

FIG. 8 is a top plan view of a two stone jewelry setting showing a second embodiment of my new design;

FIG. 9 is a front elevational view of FIG. 8, the rear view being a mirror image;

FIG. 10 is a side elevational view of a FIG. 8;

FIG. 11 is a bottom plan view of FIG. 8;

FIG. 12 is a top plan view of a two stone jewelry setting showing a third embodiment of my new design, the remaining views corresponding to those of the first embodiment;

FIG. 13 is a top plan view of a two stone jewelry setting showing a fourth embodiment of my new design;

FIG. 14 is a bottom plan view of FIG. 13, the remaining views correspond to those of the first embodiment;

FIG. 15 is a top plan view of a two stone jewelry setting showing a fifth embodiment of my new design;

FIG. 16 is a front elevational view of FIG. 15, the rear view being a mirror image;

FIG. 17 is a side elevational view of FIG. 16; and,

FIG. 18 is a bottom plan view of FIG. 16.
